UNITED STATES PATENT OFFICE

CHARLES BUFORD WILLIAMS, OF NASHVILLE, TENNESSEE

TARIFF BINDER

Application filed July 28, 1930. Serial No. 471,265.

This invention relates to a binder which is mainly designed for use with tariff sheets used by railroads, publishing agents, etc.

The general object of this invention is to provide a third leaf for the binder which acts to prevent the sheets from folding or doubling up, which soon causes damage to the sheets.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:—

Figure 1 is a perspective view of the improved binder, showing the sheets therein.

Figure 2 is a section on line 2—2 of Figure 1.

Figure 3 is a view showing the front leaf of the binder in raised position and the sheets unfolded.

Figure 4 is a view showing how the central leaf of the binder is raised to permit inspection of the sheets under the same.

Figure 5 is a section on line 5—5 of Figure 2.

In these views, the numeral 1 indicates the bottom cover leaf of the binder and the numeral 2 the top or front leaf thereof. In carrying out my invention, I connect a third leaf 3 with the front leaf, the two leaves being preferably formed of a single sheet of material formed with the fold lines 4 and 5 so that the line 4 forms a hinge for the top leaf 2 and the line 5 a hinge for the leaf 3. The rear edge of the bottom leaf is folded over, as shown at 6, and the fasteners 7 are carried by the folded-over part, these fasteners passing through eyelets in the folded part 6 and also in the rear part of the leaf 3 between the fold lines 4 and 5. The tariff sheets 8 are placed between the leaves 1 and 3, as shown, and then the leaf 3 is folded down and the outer parts of the sheets 8

folded upon the same, as shown in Figures 1 and 2. Thus this leaf 3 holds the sheets in a flattened condition and prevents the same from doubling up or becoming further folded.

It will, of course, be understood that when the device is used with small sheets, such sheets are placed between the leaves 1 and 3 and the leaf 3 acts to hold the sheets in a flattened condition and prevents the sheets from doubling up or becoming folded.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:—

1. A binder of the class described comprising a bottom cover leaf having a rear marginal portion folded over upon the leaf, fastening means carried by said rear portion, a top and a center cover leaf formed of one piece of material having parallel scored lines adjacent its center, one forming a hinge for the top leaf and the other for the central leaf, that part of the sheet between the fold lines having perforations for receiving the fastening means.

2. A binder of the class described comprising a bottom cover leaf, a top and a center cover leaf formed of one piece of material having parallel scored lines adjacent its center, one forming a hinge for the top leaf and the other a hinge for the center leaf and means for detachably connecting that part of the piece of material between the fold lines to the rear marginal portion of the bottom cover leaf.

In testimony whereof I affix my signature.
CHARLES BUFORD WILLIAMS.
